UNITED STATES PATENT OFFICE

JULIUS J. MOJONNIER, OF OAK PARK, ILLINOIS, ASSIGNOR TO MOJONNIER BROS. CO.,
A CORPORATION OF ILLINOIS

CONVEYER STOP MECHANISM

Application filed January 9, 1931. Serial No. 507,653.

The present invention relates to conveyer stop mechanisms of the class wherein articles being conveyed along a given path may be stopped and separated slightly so as to be readily taken from the conveyer by an attendant.

The invention has been worked out in connection with the handling of bottle cases and will therefore be described in that connection. Such cases usually are in box form with vertical end walls which tend to fit snugly against each other as the cases travel along in the conveyer especially where the latter is of the drag type, a type now commonly used for this purpose. When the ends of adjacent cases fit snugly together in this way, it is almost impossible to grasp the ends of a case by the hand-holds formed therein. It is therefore a difficult task to remove a case from the conveyer, although in many kinds of work this is quite desirable and in other kinds absolutely necessary. Even though a conveyer which is not of the drag type be employed, still the objectionable close fitting of ends may occur.

In carrying out my invention, I preferably provide a stop in the path of travel of the conveyer. Then when the articles being conveyed are advanced so that the foremost engages the stop, its rear end is separated from the forward end of the next article so that the foremost article may be readily grasped and removed from the conveyer. Preferably this separation of the adjacent portions of the first two articles is brought about by elevating the path of their travel at the point where the two articles come together when one of them engages the stop. Thus while the forward end of the first article engages the stop, its rear end is elevated above the level of the forward end. In the preferred embodiment the track or floor of the conveyer is humped up at the point where the first and second articles contact and consequently the forward end of the second article is elevated the same as the rear end of the first article. If the articles be box-like cases, such as I have referred to, having their ends slotted to provide hand-holds, then the rear end of the first case and the front end of

the second case are moved apart at their tops to leave the hand-holds exposed for use. Since no obstructing case is found in advance of the first case, i. e. the one against the stop, both hand-holds of the first case are available 55 to the attendant and that case can be readily removed from the conveyer.

Having pointed out the general nature of the invention, attention may now be given to the following detailed description of the preferred embodiment, and suggested modifications, which will give a clearer and fuller understanding of the invention. The description should be taken in connection with the accompanying drawings wherein the different forms of the invention are illustrated. For a measure of the invention reference should be had to the appended claims.

In said drawings, Fig. 1 is a plan view of a portion of a conveyer having a stop mechanism constructed in accordance with the present invention; Fig. 2 is a side elevation of the same; Fig. 3 is a side elevation of a portion of the structure of Fig. 2 illustrating a modified stop member; Fig. 4 is a diagrammatic view illustrating an additional conveyer upon which the articles freed from the stop may be placed; Fig. 5 is an end elevation of the structure of Fig. 1; Fig. 6 is a transverse vertical section of the same taken on a plane indicated by the line 6—6 of Fig. 1; Fig. 7 is a detailed section through the stop roller of the preferred structure, the plane of section being indicated by the line 7—7 of Fig. 2; Fig. 8 is a vertical longitudinal section of the structure of Fig. 1, the plane of section being indicated by the line 8—8 of Fig. 1; and Fig. 9 is a diagram similar to Fig. 4 illustrating the stop mechanism in association with a single conveyer for delivering the articles to the stop and receiving them after they have been freed from the stop. Throughout these views like characters refer to like parts.

The conveyer structure is similar to that shown and described in my prior Patent No. 1,714,721, granted May 28, 1929, and it comprises a supporting frame and conveyer chain. The supporting frame comprises longitudinal side members 10 connected to

gether by transverse U-shaped yokes 11 and provided with legs 12 having adjustable feet 13. All these parts are preferably metal and the legs may be of channel iron as illustrated.

5 The latter are secured at their upper ends to the vertical portions of certain of the yokes 11 by screw bolts 14 or like means. The yokes 11 may be variously secured to the side members 10. In the present instance screw bolts 10 15 perform this function. The feet 13 may be adjusted with reference to the legs 12 to suit irregularities in the floor upon which the conveyer is set and the different pairs of legs 12 are each spaced and laterally braced 15 by a transverse rod 15^a having positioning nuts 15^b, clamping blocks 15^c and retaining nuts 15^d. In the particular embodiment shown in Fig. 1, the yoke members 11 are reinforced by additional longitudinal members 20 16 which extend between the two pairs of legs 12 illustrated. In this case bolts 17 secure the parts together. Besides having the side members 10 the conveyor frame has metal strips set on edge which serve as guides 18 25 for the cases 19 which the conveyer is designed to carry. Obviously, these bottom guides might be differently formed and other forms of bottom structure might be shaped to give a proper conveyer surface and also 30 30 the hump relied upon to elevate the ends of adjacent cases, hereinafter more fully set forth. These side members 10 and bottom strips 18 form a passageway or runway for the cases 19.

35 In service the cases are placed end to end upon the conveyer and they travel in this relative position in the direction indicated by the arrows in several figures. When so traveling the cases engage the top edges of 40 the guides 18 and at the same time are kept in the confines of the conveyer passageway by the side members 10. The latter have extensions 10^a which raise the sides of the conveyer channel at a point about a case length 45 from its end, the point where the ends of the first two cases are to be separated.

The conveyer chain 20 is in structure similar to the chain illustrated in my aforesaid patent but preferably has shorter links. The 50 upper case-engaging surfaces of the links are rounded. These rounded upper surfaces extend slightly above a horizontal plane through the upper edges of the guides 18; at least this is true for the greater portion of 55 the length of the conveyer. As we shall see, when the cases approach the stop position, this relation changes and the guides rise to a higher level.

The conveyer chain 20 passes over a sprocket 60 wheel 21 having its shaft 22 journaled in bearings 23 formed in the upper ends of brackets 24 supported upon one of the U-shaped members 11 and secured thereto by bolts 25 or other suitable means. The upper 65 stretch of the chain 20 is carried along a strip

or bar, preferably a channel bar 26, supported at intervals by cross members 27. In like manner the lower stretch of the channel 20 travels along a similar bar 28 supported by the horizontal portions of the members 11. 70 The sprocket wheel 21 is shown as a guiding wheel but obviously it might be a driving wheel for the chain; or yet another wheel, or wheels, not shown, might serve this purpose. Indeed any desired driving arrangement for the chain may be employed. 75

At the extreme delivery end of the conveyer is a stop roller 29 having a central shaft 30 which is journaled in bearings formed in the side members 10 or in lieu of the bearings 80 the shaft 30 may simply extend through openings in these side members. The shaft or rod 30 is held in place by end nuts 31. The roller 29 is free to rotate. This may be accomplished by having the roller 29 secured to the rod 30 85 and having the latter rotate in the bearings in the side members 10 or the rod 30 may be held firmly and the bore through the roller 29 made large enough to allow the roller to rotate upon the rod. In lieu of the rotating 90 roller 29, I may employ a fixed stop member 32 which may take the form illustrated in Fig. 3, that is to say, to have a rounded upper surface similar to that of the roller and be provided at its ends with flanges 33 apertured for securing bolts 34 by which the stop bar may be secured to the side members 10. 95

Since in the conveyer proper the cases are engaged by the links of the chain 20 as the latter travels along, they will be carried 100 along just as in the conveyer of my prior patent. With such construction it is possible to hold one of the cases 19 without stopping the chain 20. In such event the chain will merely slip along under the case. However, 105 should the hold upon the case be released, then the friction between the case and the chain will be sufficient to cause the chain to drag the case forward.

In the embodiment illustrated, the cases 110 19 may be shoved along over the guides 18 by the chain 20 until the front end of the foremost case 19 engages the stop 29. In such event the second case 19 will press against the first and the third against the second and 115 so on, the rear-most cases being acted upon by the conveyer chain 20. As shown, the cases 19 are provided with apertures 35 through which the fingers of an attendant may be thrust for the purpose of grasping the case to lift it. 120 Since these cases are also intended for bottles they are also provided with longitudinal and transverse partitions 36 and 37 as is common in articles of this sort. If I examine the ends of the second and third cases 19, as 125 the parts appear in Fig. 8, for example, I see that the hand-holds provided by the openings 35 are not available to be grasped where the case ends fit snugly against each other, as in the case of the contacting ends of the sec- 130

ond and third cases 19. Since the chain is constantly dragging upon the cases 19 in this part of the conveyer, it would not be possible to readily separate these cases at this point so as to make it possible to use the hand-holds.

However, if I pass to the point between the first and second cases 19, I find that their adjacent ends are separated near the top so that the hand-holds are free to be used. In that case the separation of the ends of the cases is brought about by elevating the guides 18 so as to produce a hump or summit 38 over which the cases pass. On one side of the summit is an incline downward toward the chain 20, and on the other side of the summit is a similar incline downward toward the stop 29. Because of these opposite inclinations, the adjacent ends of the two cases, meeting at the summit, are angularly disposed, the ends contacting where they engage the guides and being some distance apart at the tops. It will be noted that the summits 38 of the guides 18 are distant from the stop 29 a distance equal to the length of one case 19.

In operation the drag of the chain will be sufficient to force the cases up over the humps 38 and bring the foremost case into contact with the stop. When a case reaches this position, it can be readily grasped by the attendant and lifted from the conveyer. Where the stop is the rotatable roller 29, the upward manual pull upon the case will meet with little resistance on the part of the stop as the latter will turn under the pull and make the removal of the case from the conveyer easy. As soon as one case is thus removed a second case will be forced up against the stop and again the humps 38 upon the guides 18 will separate the adjacent ends of the first two cases just as before leaving the foremost to be removed in the manner just explained. In case the fixed stop 32 is used, the resistance to the removal of the first case may be a little greater but it is obvious that with a stop of metal or like material, well rounded, the forward edge of the case will slip readily over the curved surface of the stop as the case is being elevated.

In the form of the invention illustrated in Fig. 1, the conveyer is a terminal conveyer and the cases removed are placed on a platform or otherwise disposed of. Instead of placing them upon a platform, another conveyer might be arranged just beyond the roller 29 and the cases might be placed upon this other conveyer. Such an arrangement is shown in Fig. 4. There the conveyer chain 20 is shown in association with the sprocket wheel 21 and a second like conveyer 39 is shown in association with a sprocket wheel 40. In this instance the second conveyer chain 39 is associated with guides 41 which are horizontal and serve to cooper-

ate with the chain in carrying off the cases deposited on this conveyer.

Instead of having a second conveyer chain 39 and associated parts it would be possible to make use of a continuous conveyer chain 42, shown in Fig. 9, to take the place of the chains 20 and 39 of the arrangement of Fig. 4. In such event the same humped up guides 18 would be used in association with the stop 29 and the upper stretch of the chain 42. Similar guides 43 would be associated with the same stretch of the chain beyond the stop roller 29.

These diagrammatic views give some idea of the possibilities in applying the present invention to different conveyer arrangements and it will be obvious that the invention may be applied to many different conveyer arrangements. I therefore do not wish to be limited to the exact arrangements disclosed, nor do I wish to be limited to the various details of this disclosure, but I aim to cover by the terms of the appended claims all those adaptations and modifications which rightly come within the scope of my invention.

What I claim as new and desire to secure by Letters Patent of the United States is:

1. A conveyer stop mechanism comprising in combination with a conveyer chain for advancing articles carried thereby, a stop roller against which the foremost of said articles is pressed through the action of said chain upon following articles, and guides for engaging said articles from beneath as they are acted upon by said chain, said guides being elevated at a point a short distance from said roller and terminating adjacent to said roller at a level low enough to allow said roller to act as a stop for articles advanced along said guides.

2. A conveyer stop mechanism comprising in combination with a conveyer chain for advancing box-like cases having hand holds in their ends, a stop against which the foremost of a series of said cases under the action of said chain may be crowded, and guides for elevating the adjacent ends of the foremost two cases of the series while leaving their opposite ends at a lower level, the foremost case being at such time in contact with said stop, whereby the hand-holds of said foremost case may be readily used by the hands of the operator to remove said foremost case from the conveyer.

3. A conveyer stop mechanism comprising in combination with a conveyer chain for advancing box-like cases having hand-holds in their ends, a stop roller for engaging the forward end of the foremost of a series of said cases fed on by said chain, and guides for engaging said cases as they are being acted upon by said chain, said guides being elevated at a point in said conveyer distant a case length from said roller to an elevation above that of the axis of said roller,

while at a point adjacent to said roller said guides terminate at a level below that of said axis, and at a point two case lengths from said roller said guides are on a level 5 below that of the point one case length from said roller, whereby the hand-holds of the foremost case may be readily grasped to remove the case from the conveyer.

4. A conveyer stop mechanism comprising in combination with a conveyer chain for advancing articles carried thereby, a rigid stop against which the foremost of said articles is pressed through the action of said chain upon following articles, guides for engaging said articles from beneath as they are acted upon by said chain, said guides being elevated at a point a short distance from said stop and terminating adjacent to said stop at a level low enough to allow said stop to act upon articles advanced along said guides.

5. A conveyer stop mechanism comprising in combination with a conveyer chain for advancing box-like cases having hand-holds in their ends, a fixed stop against which the foremost of said cases has its lower forward end pressed through the action of said chain upon following cases, and guides for supporting said cases as they are acted upon by said chain, said guides being elevated at a point 30 a case length from said stop to its highest elevation, while at a point adjacent to said roller said guides terminate at a level below that of the top of said stop, and at a point two case lengths from said roller said guides 35 are on a level below said highest elevation, whereby the hand-holds of the foremost case may be readily grasped to remove the case from the conveyer.

6. A conveyer stop mechanism comprising in combination with chain-conveyer means for advancing articles to and beyond a stop position, a stop roller against which the foremost of said articles is pressed through the action of said means upon following 45 articles to hold said foremost article in said stop position, and guides for engaging said articles from beneath as they are acted upon by said means, said guides being located on both the incoming and outgoing sides of said 50 stop roller at substantially the same level except that they are elevated at a point a short distance from said roller on the incoming side thereof and adjacent to said stop roller on said incoming side are low enough to 55 allow said roller to act as a stop for articles advanced along said guides and to form an antifriction support for articles placed thereon and on said outgoing conveying means.

7. A conveyer stop mechanism comprising in combination with chain-conveyer means for advancing box-like cases having hand-holds in their ends to and beyond a stop position, a stop roller for engaging the forward end of the foremost of a series of said cases 65 fed along by said means on the incoming side

of said stop roller, said stop roller serving to hold said foremost case in said stop position, and guides for engaging said cases from beneath as they are being acted upon by said means, said guides being positioned on both the incoming and outgoing sides of said stop roller and being elevated at a point on the incoming side thereof distant a case length from said stop roller, to an elevation above the axis of said roller, while at a point adjacent to said roller on the incoming side thereof said guides have an elevation below that of said axis, and at a point two case lengths from said roller on the same side thereof said guides are on a level below that of the point one case length from said roller and on the outgoing side of said roller said guides approach closely to said roller and have an elevation below that of said roller, whereby the hand-holds of the case in said stop position may be readily grasped to remove said case from said position and to set it upon said roller and the outgoing portion of said chain-conveyer means.

In testimony whereof, I have hereunto set my hand this 7th day of January, 1931.

JULIUS J. MOJONNIER.
